EXTERNAL RESONANT SECTION TUBES

Ralph J. Bondley, Scotia, N.Y., assignor to General Electric Company, a corporation of New York

Application September 3, 1957, Serial No. 681,517

3 Claims. (Cl. 315—5.46)

My invention relates to improvements in electron tubes having resonant sections with portions external to the evacuated tube envelope.

Many tubes have resonant sections that are difficult to tune because the frequency determining means for the sections are contained within the evacuated tube envelope. To overcome this difficulty, tubes have been developed having portions of the resonant sections external to the evacuated envelope so that the frequency determining means such as plungers, diaphragms, or the like, can operate outside of the envelope in these external portions.

In these prior external resonant section tubes, ceramic cylinder insulators—called windows—provide the air seal between the evacuated and non-evacuated portions of the resonant sections. Because these cylinders are necessarily close to the tube electron beam, they are subjected to bombardment by stray electrons, X-rays, gas ions, and the like, that produce local heating and subsequent deterioration of the cylinders. Obviously, the resulting failures could be diminished if less insulator surface were subject to bombardment.

Accordingly, an object of the present invention is to provide an external resonant section tube having minimum window area exposed to the electron beam.

The windows in some prior external resonator section tubes provide physical support for the tube as a unit, and accordingly are made thick for strength. But thick windows are disadvantageous from a local heating viewpoint, because the amount of heat generated by dielectric loss is proportional to the volume of the windows. Further, thick windows produce a relatively large discontinuity in the resonator sections and also introduce undesired capacitance.

Therefore, another object is to provide an external resonator section tube having thin windows.

If the window and the metal to which it is sealed do not have the same thermal coefficients of expansion, the metal immediately proximate to the windows has to be thin with the result that as it expands due to heat, it does not have sufficient strength to break the windows. In a tube having a cylindrical window, this thin metal completely encircles the tube and thus is a portion of the main tube support. Consequently, these tubes are weak and often bend axially thereby causing misalignment of the drift sections along the tube axis.

Thus, a further object of the present invention is the provision of an external resonator section tube in which relatively strong thick metal provides the axial support for the tube.

The above-mentioned objects are achieved in one form of my invention by the provision of a klystron with an elongated evacuated envelope having an electron gun at one end and a collector electrode at the other end. The central portion of the envelope is comprised of a plurality of axially disposed drift sections separated by gaps. At each gap there is an individual cylindrical cavity resonator having a short center section transversely arranged

to and extending between the drift sections on either side of the respective gap. At one or both ends of each center section thin disc-shaped windows provide vacuum sealing and extending external cavity resonator portions complete the resonator. Tuning pistons mounted in the external cavity resonator portions provide conveniently accessible external tuning.

Although the specification concludes with claims particularly pointing out and distinctly claiming the subject matter that I regard as my invention, the invention may be better understood from the following description considered in connection with the accompanying drawing in which:

Fig. 1 is a side view, partly in section, of a preferred embodiment of my invention;

Fig. 2 is a cross-sectional view of my preferred embodiment along the line 2—2 of Fig. 1; and

Fig. 3 is a cross-sectional view taken along the line 3—3 of Fig. 1.

In the several figures of the drawings, corresponding elements have been indicated by corresponding reference numerals to facilitate comparison. Referring specifically to Fig. 1, the illustrated electron tube comprises an elongated envelope having an electron gun 11 at one end and a collector electrode 12 at the other end. A plurality of drift tube sections 14, 15 and 17, separated by gaps 19 and 20, extend between gun 11 and electrode 12. These gaps are bridged by resonant sections here shown to be cavity resonators 22 and 23, respectively, but that could be wave guide sections, coaxial line sections, etc. Although only two cavity resonators are illustrated, the present invention can be practiced with a tube having any number of resonators.

Electron gun 11 includes a dish-shaped cathode 25 mounted within a focusing electrode 26 and heated by a coil 28 secured by two insulating beads 29 in a pan-shaped element 31. Element 31 is separated from an oppositely disposed annular ring 32 by a cylindrical insulating member 34.

At the opposite end of the envelope, collector 12 comprises a hollow cylindrical member 35. The means for cooling collector 12, which may be a conventional water jacket, has been omitted in order to simplify the illustration. For the same reason, structure that may be conventional has not been shown for producing a magnetic field between collector 12 and gun 11.

Resonator 22 comprises a cylindrical short center section 36 across the open ends of which two disc-shaped low-loss windows 37 are vacuum sealed. These windows can be constructed of fused quartz, a ceramic, or any one of a number of other suitable materials. An air-tight seal between these windows and section 36 is needed because the center portion of the tube, including the drift sections, is evacuated. Two external cylindrical cavity resonator sections 39 are joined to the ends of section 36 by means shown to be rigid, but that could be detachable, such as spring contact fingers. Frequency determining means here illustrated as two pistons 40, that can be slid for tuning by means of rods 41, are in slidable electrical engagement with the inner wall of sections 39 through a plurality of spring finger contacts 42. Of course, other frequency determining means such as a bellows or a diaphragm could be used instead of pistons 40.

The input to resonator 22 may be provided by any suitable means such as a wave guide with an opening into the resonator or a coaxial line with a probe or a coupling loop extending into the resonator. The means shown comprises a coaxial line having an outer conductor 43 and an inner conductor 44 separated by an insulator spacer 46. Conductor 43 extends into resonator 22 in the form of a loop. Of course, the size and position

of this loop will be determined by the matching required between the coaxial line and resonator.

The support provided by section 36 is best shown in Fig. 2. This section has a center portion extending between drift sections 14 and 15 on two sides of the tube. Because this portion is not proximate to windows 37 it can be made relatively thick and strong to provide the structural support required to maintain these drift sections in axial alignment. Also, because this section surrounds most of gap 19, windows 37 have only a small area exposed to the electron beam appearing in gap 19 when the tube is in operation.

Although the circular symmetry of resonator 22 is preferred from a construction consideration, the resonators can be of other tube-like shapes, as is illustrated by the rectangular cross-sectional shape of resonator 23. This resonator has a four-sided short center section 47 extending between and supporting the drift sections 15 and 17. At the ends of section 47 there are two vacuum sealed windows 49 and two coaxial rectangular cavity resonator sections 50. Tuning of resonator 23 is provided by two rectangular pistons 52 that are slideable in sections 50 by means of rods 53. Electrical contact between sections 50 and pistons 52 is maintained by means of spring contact fingers 54. Energy, if small, can be coupled out of resonator 23 by means of a loop such as is shown with resonator 22. But in most applications the energy will be large enough to require a wave guide output and thus a wave guide 56 is shown having an opening into resonator 23. The size and position of this opening will be determined by the required matching.

The cross-sectional view of Fig. 3 shows the support given by section 43 to drift sections 15 and 17. Any tendency for these drift sections to move out of alignment is resisted by section 43 alone. Windows 49 do not provide any significant structural support but rather serve only to provide an insulated air seal for resonator 23.

The operation of the disclosed tube is conventional. That is, the input wave from the coaxial line excites resonator 22, which is tuned to the wave frequency. An electric field is thereby produced across gap 19 that affects the velocity of electrons emanating from gun 11 as they pass through this gap. When the lower end of this gap is positive with respect to the upper end, the electrons then present in the gap are accelerated positively, and during a reverse condition the electrons in the gap are accelerated negatively. The differences in acceleration produce differences in the velocities of the electrons so that as they pass through drift section 15 they tend to bunch because the fast moving electrons from a positive half cycle of the voltage across gap 19 catch up with the slow moving electrons from the previous negative half cycle. These bunches will thus arrive at gap 20 a time apart equal to a period of the input to resonator 22. Resonator 23 is tuned to the frequency of this input so that these bunches excite resonator 23, causing an amplified wave to be produced therein. This wave is coupled to the utilization device by wave guide 56.

The manner in which the disclosed structure provides the mentioned objects should now be apparent. Because the short center sections 36 and 43 of resonators 22

and 23, respectively, surround all but a small fraction of the area around gaps 19 and 20, respectively, windows 37 and 49 are subject to much less bombardment than if they were cylindrically situated around these gaps as in the prior external resonator section tubes. Also, because these windows do not bear any significant structural support, they can be constructed of thin material and thereby can diminish local heating due to dielectric loss and discontinuity in the resonant section due to the presence of the dielectric. Further, the disclosed tube is rigid because much of the structural support is provided by metal that is not immediately adjacent the windows and thus that can be made thick and thereby very strong. From the above it should be evident that the disclosed tube is not only subject to less window failures, but is mechanically more rigid than the prior tubes with the result that the drift sections remain in alignment.

Although the invention has been described with respect to certain specific embodiments, it will be appreciated that many modifications and changes may be made by those skilled in the art without departing from the spirit of the invention. I intend, therefore, by the appended claims, to cover all such modifications and changes as fall within the true spirit and scope of the invention.

What I claim as new and desire to secure by Letters Patent of the United States is:

1. An external resonant section tube comprising an electron gun for emitting electrons, a collector electrode spaced from said electron gun, for receiving electrons from said electron gun, a plurality of metallic drift tube sections extending axially between said electron gun and said collector electrode and spaced to produce a gap, a resonant section positioned to bridge the gap between two adjacent of said drift sections, said resonant section comprising a tube-shaped metallic center section rigidly extending between said two adjacent drift tube sections with the axis thereof transverse to the axis of said drift tube sections.

2. The external resonant section tube as defined in claim 1 and including two dielectric windows vacuum sealed respectively to opposite ends of said center section.

3. In an external resonant section tube, an elongated envelope comprising a plurality of axially-arranged metallic drift tube sections extending axially and spaced to produce a gap, a resonant section positioned to bridge the gap between two adjacent drift sections, said resonant section comprising a tube-shaped metallic center section rigidly extending between said two adjacent drift tube sections with the axis thereof transverse to the axis of said drift tube sections, two dielectric windows vacuum sealed to opposite ends of said center sections, and frequency-determining means for tuning said resonant sections.
